US00D945620S

(12) **United States Design Patent** (10) **Patent No.:** **US D945,620 S**
(45) **Date of Patent:** **** Mar. 8, 2022**

(54) **GREAT TOE IMPLANT**

(71) Applicant: **BioPoly, LLC**, Fort Wayne, IN (US)

(72) Inventors: **Herbert E. Schwartz**, Fort Wayne, IN (US); **Matthew L. Mroczkowski**, Fort Wayne, IN (US); **Stone Miguel**, Fort Wayne, IN (US)

(73) Assignee: **BioPoly, LLC**, Fort Wayne, IN (US)

(**) Term: **15 Years**

(21) Appl. No.: **29/722,418**

(22) Filed: **Jan. 29, 2020**

(51) LOC (13) Cl. **24-03**

(52) U.S. Cl.

USPC **D24/155**

(57) **CLAIM**

The ornamental design for a great toe implant, as shown and described.

DESCRIPTION

FIG. 1 is a top perspective view of a great toe implant comprising the new design;

FIG. 2 is a bottom perspective view of the design of FIG. 1; FIG. 3 is a side elevational view of the design of FIG. 1, where the front and back views are mirror images; FIG. 4 is a top view of the design of FIG. 1; and, FIG. 5 is a bottom view of the design of FIG. 1.

The consistent oblique line shading represents a contrast in appearance.

1 Claim, 4 Drawing Sheets
